UNITED STATES PATENT OFFICE.

ALEXANDER EKLUND, OF ATTLEBORO, MASSACHUSETTS, ASSIGNOR TO GENERAL CHAIN COMPANY, OF PROVIDENCE, RHODE ISLAND, A CORPORATION OF MASSACHUSETTS.

BRACELET.

Application filed September 22, 1925. Serial No. 57,909.

This invention relates to improvements in the construction of bracelets or chains of the extendible type, and has for its object to provide a bracelet of this character having 5 means whereby the links may be readily disconnected one from the other for the purpose of inserting or removing one or more links to vary the operating length of the bracelet.

A further object of this invention is to 10 construct certain of the links with separable jaws or arms releasably snapped together at one end, the same being disconnected or separated by the doubling or folding of two adjacent links of the bracelet connected 15 thereby back upon each other.

A still further object of the invention is to 20 construct a separable connecting link of two separate jaw or arm members hinged together at one end and curved at their opposite ends to be snapped one over the other.

With these and other objects in view, the 25 invention consists of certain novel features of construction, as will be more fully described, and particularly pointed out in the appended claims.

In the accompanying drawings:

Figure 1 is a side elevation showing my improved bracelet connected to the opposite sides of a watch.

Figure 2 is a perspective view of the band-shaped link forming the side walls of the bracelet structure.

Figure 3 is a perspective view of one of the arm members of my connecting link.

Figure 4 is a perspective view of the other of the link jaw members of the connecting link.

Figure 5 is a perspective view showing the jaw members of the connecting link hinged together at one end and separated at their opposite ends.

Figure 6 is a perspective view illustrating the doubling or folding back of the adjacent links of the bracelet upon each other, whereby the jaw members of the connecting link are caused to be separated from each other, to permit the disconnection of the links of the bracelet.

Figure 7 is a sectional side elevation of the 50 bracelet in contracted position.

Figure 8 is a sectional side elevation showing the bracelet in expanded position.

Figure 9 is a sectional end elevation on line 9—9 of Figure 7.

It is found in the practical construction 55 and use of bracelets of this character, of advantage to provide means whereby the different links may be readily disconnected one from the other for the purpose of adding or removing one or more links to adjust the 60 working length of the bracelet and also to provide a bracelet, the jaws of the connecting links of which may be pried apart or separated by the doubling of the adjacent bracelet links back of one upon another, and 65 to accomplish this result, I have constructed a bracelet as hereinafter described, in which the connecting link is formed of two separable arms or jaws, hinged or otherwise connected together at one end and snapped together at their opposite ends; and the following is a detailed description of the present embodiment of my invention, showing 70 one means by which these advantageous results may be accomplished:—

With reference to the drawings, 10 designates a band-shaped link which may be folded up from a strip of sheet stock, to provide channel-shaped side walls 11, with connecting cross bars 12 and 13 at either end, the cross bar 12 at one end being integral with both of the side walls, and cross bar 13 being formed of two portions turned inwardly toward each other from the opposite side walls, one of the portions 14 having a lateral projection 15 rolled over the opposite portion 16 to firmly bind the two parts together and hold the whole in substantially rectangular shape. The upper and lower edges 17 of the side walls 11 are turned or 85 folded inwardly to provide a channel 18, for the purpose hereinafter described.

The connecting band link is formed of two arms or jaw members 19 and 20, the member 20 being provided with a bent up 95 end piece 21 which has suitable extension 22 to slidably engage the channel 18 of the aforesaid band link. This end piece is also provided with a slot opening 23, to receive the tongue 24 on the opposite jaw member, to 100

hingedly secure these two portions together. The end opposite the hinged end of the lower jaw 20 is rolled or turned inwardly as at 25 and has a longitudinally projecting portion 26 substantially parallel with said main jaw member to extend a substantial distance over the engaged cross bar of the opposite band link forming a hook to prevent complete disengagement from the end bar of the band link thereby requiring further manual manipulation for separating the parts, and the corresponding free end of the opposite jaw 19 is curved as at 27 to snap over the inwardly-curved portion 25 of the lower jaw to firmly lock the two together.

The links previously described are assembled by placing one of the cross bars of the side wall forming band links between the jaws of the connecting link and positioning a spring 28, between the cross bar and the end portion 21 of the connecting link, and the opposite cross bar of the side wall, forming a link, may then be inserted to be disposed under the lip portion 26 of the connecting link, after which the free ends of the jaws may be snapped together to securely hold the two links in their assembled relation. This operation may be repeated until the desired length of bracelet is produced after which end hooks 29 may be secured to the bracelet ends by which the same may be attached to a watch 30, if desired.

In case it is desired to detach the links of the bracelet to remove one of the links or to add a link for extending or adjusting the working length of the bracelet the jaws of the connecting links may be readily opened by merely doubling two of the adjacent link units of the bracelet back upon themselves, as illustrated in Figure 6, whereby a prying action between these links acting on the connecting links serves to separate its arms or jaws, as shown in Figure 6, after which by suitable manual manipulation the hook portion 26 of the jaw link 20 may be disconnected.

It will be readily apparent that the broad top surface and the side walls of the links may be suitably ornamented to enhance the appearance of the bracelet, it being also apparent that the portions at the ends of the connecting links where the greatest strain is apt to occur, are strengthened by the rolling in of both ends of the jaw members to overlap one another.

From the foregoing, it will be seen that I have produced a bracelet of a structure having a novel detachable connecting means and yet a bracelet which is practical in construction and operation.

The foregoing description is directed solely towards the construction illustrated, but I desire it to be understood that I reserve the privilege of resorting to all the mechani-

cal changes to which the device is susceptible, the invention being defined and limited only by the terms of the appended claims.

I claim:

1. An extendible bracelet chain structure comprising a series of band links, connecting links therefor having separable jaws resiliently snapped together at one end, and means responsive to the doubling of said chain upon itself for separating said jaws. 75

2. An extendible bracelet chain structure comprising a series of band links forming side walls of the structure and connecting band links therefor separable at their ends and forming top and bottom walls, one of 80 said connecting band links being separated at one of its ends upon said chain structure being doubled back upon itself to permit said connecting band link to be detached and separated from the next of said series of 85 band links.

3. An extendible bracelet chain structure comprising a series of band links disposed to form side walls for said structure, connecting band links therefor disposed to form 90 top and bottom walls and comprising two jaw members hinged together at one end and resiliently releasably secured together at the other end, the jaw members of one of said connecting links being separated upon said 95 chain structure being doubled back upon itself whereby the links may be detached and separated.

4. An extendible bracelet structure comprising a series of band links, and a series 100 of connecting links therefor each composed of two separate sheet metal jaws hingedly connected together, the free ends of each jaw being curved inwardly to snap one over the other by its inherent resiliency, and a 105 spring acting between said band link and connecting link to move them to contracted position.

5. An extendible bracelet structure comprising a series of band links each having 110 side walls, channel shaped in cross section with cross bars at their ends, connecting links embracing the cross bars of two adjacent band links and each having two jaw members hingedly connected together at one end and 115 releasably snapped together at the opposite end and projections on one of the members of said connecting link to extend into said channel side walls to guide the connecting link in its sliding movement. 120

6. An extendible bracelet structure comprising a series of band links each having side walls with cross bars at their ends, connecting links embracing the cross bars of two adjacent band links and each having two jaw members hingedly connected together at one end and curved inwardly to be snapped together at the opposite end, one of said curved ends being bent inwardly sufficiently 125 to form a hook to extend a substantial dis- 130

tance over the cross bar to prevent inadvertent removal of the same.

7. An extendible bracelet chain structure comprising a series of band links, links having separable jaw members connecting said band links to fold one upon the other, and means whereby the folding action of said band links serves to exert an opening action on the jaw members of this connecting link.

10. 8. An extendible bracelet chain structure

comprising a series of band links, links having separate jaw members hinged together and disposed to connect said band links so that they may fold one upon the other, and means in said band links so arranged that the folding of said links will cause the jaws of their connecting links to open. 15

In testimony whereof I affix my signature.

ALEXANDER EKLUND.
